UNITED STATES PATENT OFFICE.

CALVIN R. WAID, OF BIRMINGHAM, ALABAMA.

SEGMENTAL GRATE-BAR.

1,175,094.

Specification of Letters Patent. Patented Mar. 14, 1916.

Application filed May 28, 1915. Serial No. 30,991.

To all whom it may concern:

Be it known that I, CALVIN R. WAID, a citizen of the United States of America, residing at Birmingham, in the county of Jefferson and State of Alabama, have invented 5 certain new and useful Improvements in Segmental Grate-Bars, of which the following is a specification.

My invention relates to an improvement 10 in grate bars formed by a plurality of segments or units comprising each a fire head and a base and which are assembled in a novel manner. Preferably the fire head and base of each segment are cast integral 15 and the improved means for assembling the segments to form the bar consists of a pair of side straps tied together at intervals by bolts inserted between the bases of segments, which bases are preferably reduced to provide bolt spaces and also tapered to facilitate 20 their ready insertion between the side bars.

One feature of my invention relates particularly to the shape given the bases of the segments. The lower ends of these bases 25 are tapered as viewed from the end of the bar and are reduced with reference to the upper portions of the bases as viewed from the side of the bar, this latter arrangement provides the vertical spaces designed to receive 30 the tie bolts for the side bars between and to permit the segment bases to be lifted up and withdrawn from the bar without interfering with such bolts.

My invention further contemplates providing 35 a novel means for fastening the segments in assembled position, such means consisting in the provision of alining side notches in the bases of the several segments and mounting arched plates in the alining 40 notches along each side of the composite bar, such plates being arched in vertical cross section and adapted to be drawn together by their tie bolts and expanded against the segment bases until their top 45 and bottom edges positively engage the top and bottom edges of the notches and give a firm but light bracing connection which holds the grate bar rigid.

A further feature of my invention is to 50 adapt the arched brace plates to form longitudinal ventilating channels between them and the segment bases to thereby counteract a tendency of the bar to warp under excessive heat.

My invention further contemplates in-

creasing the prevention against over heating in the segment bases by providing the latter in each side face with vertical grooves and forming registering transverse air channels or ventilating passages which intersect the grooves and permit the air to flow up between and longitudinally through the bases of the segments.

A further advantage arising from the design of my bar segments is that I reduce to a minimum the number of different parts required to build up the bar, for the several intermediate segments are all made reversible and interchangeable and the end segments carrying integral cast trunnions are also duplicates and all parts are designed so that they may be cast without the use of cores or split patterns to thereby simplify and reduce to a minimum the cost of manufacture of the bar. In making the segments reversible it is essential that they should be symmetrical with reference to a vertical transverse central plane, which results in the segment bases having equal spacing shoulders or offsets on each side by means of which I dispense with right and left handed segments and I require no blank segments for building up the bar.

My invention further comprises the novel details of construction and arrangement of parts, which in their preferred embodiment are hereinafter more particularly described and illustrated in the accompanying drawings which form a part of this specification.

Figure 1 is a side elevation of a grate bar 90 constructed in accordance with my invention. Fig. 2 is a partial plan view of Fig. 1. Fig. 3 is an end view of Fig. 2 showing a segment partially inserted between the arched side plates. Fig. 4 is a view similar to Fig. 3 with the segment driven home and interlocked with the side plates.

Similar reference numerals refer to similar parts throughout the drawings.

I have illustrated my invention in the accompanying drawings in its preferred embodiment only and as shown the bar comprises a series of intermediate segments which are all similar and interchangeable and which each comprise an arched fire head 105 10 cast integral with a base 11 which is offset equi-distantly on each side from the fire head and which is provided with a bottom extension 12 of less thickness than the base 11 and preferably tapers downwardly in 110

width. The side edges of the base 11 and its extension 12 are provided with shoulders 13 and 14, which are formed by side notches in the base portion of each segment. The 5 bottom end of the extension 12 is sharply tapered at 15 and a vertical groove 16 extends centrally and longitudinally along each side face of the base portion upwardly toward the fire head until it terminates at 10 a ventilating opening 17 through the lower middle portion of the fire head 10. This opening 17 has roughly the shape of a triangle with its corners rounded and its lower corner projects well into the base portion 11 of the segment so that the latter is divided by opening 17 and groove 16 into two offset shoulders which alone engage and serve to space the assembled segment bases. At 15 an intermediate point in the base and intersecting the ventilating grooves 16 therein I provide a vertically elongated ventilating port 18. The upper edges 19 of the spacing shoulders of the base 11 on each side of the groove 16 slope to the side edge of the base 20 and overhang the side plates 21. The ventilating openings 17 and 18 through the segment are spaced just far enough to provide the requisite strength in the segment while permitting any broken or defective segment 25 to be readily split when it is necessary to remove it independently from the side bars in the manner hereinafter described.

The grooves 16 of the abutting faces of adjacent segments, as seen more fully in Fig. 35 2, will register and form vertical ventilating channels extending upwardly between each adjacent pair of segments. As seen in Fig. 1, the reduced widths of the base extensions 12 provide vertical transverse passages between them which serve to additionally ventilate the segments and, as above stated, to provide recesses for the reception of the cross bolts 20 by means of which the retaining side plates or bars 21 are held together 40 and in interlocked engagement with the segment bases. The end segments are similar to the intermediate segments with the exception that on one side face thereof a boss 45 22 is cast thereon and integral with this is a cast trunnion 23. The base portion of these 50 end segments differs from that of the intermediate segments in that it has a side enlargement at an intermediate point to provide for a transverse bolt hole therethrough 55 for the end bar retaining bolt 20. The enlargement is offset on the same side as the boss and trunnion, leaving the inner side face of the segment similar to that of the adjacent segment. By providing two similar 60 end segments and reversing their trunnions I form the ends of the bar without requiring special castings for right and left hand end segments. One or more of the intermediate segments are provided with integral shaker arms 24 formed by an extension 65

of its lower end 12 and being adapted for connection to a shaker bar (not shown), in any well understood manner.

The fastening means for the segments comprise side bars or plates 21 and these are preferably formed by rolled metal plates shaped slightly concavo-convex in vertical transverse cross section and adapted to be tied together at various points by the cross bolts 20. These bars have their concave faces turned so as to provide not only a longitudinal ventilating channel between their inner faces and the segment bases opposite them, but also to so dispose the bar that it is adapted to be spread by tightening its bolts into positive interlocking engagement with the shoulders 13 and 14 of the segment bases.

In assembling the bar the side plates 21 are first bolted loosely to the end segments; 85 the several intermediate segments are then inserted between the side bars; the intermediate bolts are inserted; and all bolts are then drawn tight, thereby clamping the whole bar together and interlocking its parts to form a rigid structure. The advantage of having the bases taper in side elevation is that by this means I provide what I term a quick repair bar, as, in the event of the breaking of or injury to a segment, I can remove it by either splitting it and letting it fall through between plates 21, or chipping off the shoulders 14 when the base can be drawn upwardly from between the plates 21, and a repair segment can be 100 inserted in the bar to replace it by driving its tapered base in between side bars in the manner shown in Fig. 3 until the latter snaps into place in the side notches. Such 105 repairs can be made without removing the bar from the furnace or entirely withdrawing the fire.

One feature of advantage in connection with my end segments is that they are so designed as to be capable of being cast integrally without cores and without split patterns and no machine work is required. It will be noted in the manufacture of my bar that only three patterns are required, one for the intermediate segment, one for the 110 shaker arm segments, and one for the end segment. The concave side straps or plates provide a much lighter and better ventilated bar than where heavy solid side bars are used and they lend themselves particularly 115 to provide an interlocking means for the segment bases which will prevent rattling and which, being more flexible than a solid bar, will line them up without requiring the machining of the side notches in the 120 bases.

Having thus described my invention, what I claim as new and desire to secure by Letters Patent, is:—

1. In a sectional grate bar, a series of seg- 130

ments having bases with side notches which are disposed in alinement, arched plates seated in said notches, and means to draw said plates inwardly into the notches and spread their top and bottom edges into engagement with top and bottom walls of the notches, substantially as described.

2. In a sectional grate bar, a series of segments having bases with side notches which are disposed in alinement, arched plates 10 with their concave faces turned inwardly which are seated in said notches, and means to tie said plates together to hold the bar segments interlocked thereby, substantially as described.

3. In a sectional grate bar, a plurality of units, each formed in a single piece and each having a fuel supporting head and a spacing base, alining notches on each side edge of 20 said bases forming longitudinal channels along each side of the bar, a metal plate which is curved transversely to its length and seated in each channel with its concave wall inturned, and cross connections which 25 pass through the bar and plates and are adapted to draw the plates together against the bases and spread their top and bottom edges into bracing engagement with the top and bottom walls of the notches.

4. In a sectional grate bar, a series of segments having bases, alining notches on each side of said bases forming longitudinal channels along each side of the bar, an arched metal plate seated in each channel 30 with its concave wall inturned, said channels having undercut top and bottom walls with which the top and bottom edges of said 35 plates when spread apart are adapted to interlock, and cross connections which pass through the bar and plates and are adapted 40 to draw the plates together against the bases and spread their top and bottom edges into interlocking and bracing engagement with the undercut top and bottom walls of the 45 notches.

5. In a sectional grate bar, segments comprising each an integral fire head and a base, the bases being adapted to abut in assembled 50 position to space the fire heads, grooves disposed in the sides of the bases and arranged in alinement on each side, side bars adapted 55 to fit in said side grooves and interlock the segment bases in assembled position, the side bars being shaped to provide longitudinal 60 ventilating passages extending between them and the side walls of the bases, and said bases having vertical ventilating passages formed between their abutting faces and having longitudinal alining openings which 65 register with and are disposed in a line which intersects the vertical passages, substantially as described.

6. In a sectional grate bar, segments comprising each an integral fire head and base, 65 the bases being adapted to abut in assembled

positions in their upper portions and being reduced in their lower portions to leave vertical transverse ventilating spaces which open down through the bottom of the bar, side retaining members, and cross connections for said members adapted to pass 70 through said spaces, substantially as described.

7. In a sectional grate bar, segments comprising each an integral fire head and a base, 75 which base is widest at the upper portions thereof and which is offset equi-distantly at each side of the fire head and bottom end of the base, side retaining members, shoulders on the segment bases adapted to interlock 80 with said members, and cross connections inserted between the segment bases and below their abutting portions, substantially as described.

8. In a sectional grate bar, segments comprising integral fire heads and bases, the end segments having integral trunnions cast thereon, alining side notches provided in the end and intermediate segments, side bars adapted to seat in said notches, end bolts 90 which pass through the end segment bases and engage said side bars, and intermediate bolts which connect the side bars and which are interposed between the reduced lower ends of the segment bases, said intermediate 95 segment bases being reduced throughout their lower portions to form transverse bolt receiving spaces having substantially parallel side walls.

9. In a segmental grate bar, a segment 100 cast integrally and comprising a fire head and a base, the base being off-set equi-distantly on each side of the fire head and being widest at its upper portion and reduced in thickness in its lower portion and having its side edges relatively inclined to taper downwardly, and a notch in each side edge, substantially as described.

10. A grate bar segment comprising an integral fire head and base, the base being 110 offset equi-distantly on each side of the fire head and having its lower portion of reduced thickness and having its side edges downwardly tapering, notches in the side edges of its base, and vertical ventilating 115 grooves extending up each side face of the base and opening through the upper portion thereon on each side of the fire head, substantially as described.

11. A grate bar segment comprising an 120 integral fire head and base, the base being offset equi-distantly on each side of the fire head and having its lower portion of reduced thickness and having its side edges 125 downwardly tapering, notches in the side edges of its base, and vertical ventilating grooves extending up each side face of the base and opening through the upper portion thereon on each side of the fire head, said fire head having a transverse opening at the 130

upper end of said grooves, substantially as described.

12. A grate bar segment comprising an integral fire head and base, the base being 5 thickest at its upper end and reduced in its lower portion in thickness and having its side edges downwardly tapered and notched, the bottom side edges below the notch being sharply tapered inwardly, substantially as 10 described.

13. In a sectional grate bar, a series of segments having abutting bases which have 15 their side edges downwardly tapered and notched, side retaining arched bars adapted to engage in the side notches of the segment bases and to spring apart for the insertion of said tapered bases between them, and

means to fasten the side bars in interlocking engagement with said notches, substantially as described.

14. In a sectional grate bar, a series of segments comprising fire heads and bases having notched side edges which taper downwardly and which are disposed in alinement, arched side plates adapted to 25 engage in said notches and hold the segment bases in interlocked abutting position, and cross connections for said plates which pass between and below the abutting portions of intermediate segments.

In testimony whereof I affix my signature.
CALVIN R. WAID.
